UNITED STATES PATENT OFFICE.

EDWARD O. SCRIVEN, OF NEW YORK, N. Y., ASSIGNOR TO WESTERN ELECTRIC COMPANY, INCORPORATED, OF NEW YORK, N. Y., A CORPORATION OF NEW YORK.

OSCILLATION GENERATOR.

1,418,739.

Specification of Letters Patent. Patented June 6, 1922.

Application filed June 4, 1917. Serial No. 172,646.

To all whom it may concern:

Be it known that I, EDWARD O. SCRIVEN, a citizen of the United States, residing at New York, in the county of New York and State of New York, have invented certain new and useful Improvements in Oscillation Generators, of which the following is a full, clear, concise, and exact description.

This invention relates to oscillation generators, and particularly to vacuum tube oscillators.

It is well known in the art that a vacuum tube repeater of the audion type, for example, may be made to oscillate by providing a feed-back connection from the output to the input circuit of the device, and by providing a condenser suitably placed in the tube circuits for tuning to the desired frequency. One type of such a generator is described by Hartley in his United States Patent 1,356,763, for oscillation generators, patented October 26, 1920. The output, however, from such a generator is not constant for a given setting of the condenser and the feed-back connection, but depends upon the electrical values of the other elements of the oscillator, such as the impedance of the vacuum tube and the voltage of the direct current source.

The object of this invention is to provide means for generating oscillations, the intensity of which is independent of small changes in the impedance between the output electrodes of the evacuated vessel, so that approximately similar evacuated vessels may be used in the oscillation generator without producing any change in the high frequency output.

For the accomplishment of this object, this invention embodies in the output circuit of the oscillating tube a path of high impedance for the direct current from the source of voltage for the output circuit, and a path of low impedance for the resultant oscillations. The path of high impedance, preferably composed chiefly of a resistance, should be of such a value that the space current remains practically constant irrespective of the conditions of oscillations, and of slight changes of the output voltage source or of the impedance between the output electrodes of the evacuated tube. If the direct current remains constant, it follows, therefore, that the alternating current developed will have

the same constancy. If, now, a circuit of low impedance, preferably composed chiefly of a resistance, is provided for this alternating current, which impedance is not changed by change of frequency, an alternating voltage of constant amplitude may be obtained from this impedance which may be impressed on suitable receiving or transmitting terminals, such as the input circuit of an amplifier, or the terminals of an outgoing line.

It has also been found that, due to this constancy in the space current, the frequency generated by the oscillator for a given setting of the condenser also possesses the same constancy and is made practically independent of small fluctuations in the voltage or the electrical values of other elements in the circuit.

The output, however, from such a generator is not pure, as high harmonics are present in addition to the fundamental oscillation. It is possible to increase the intensity of the harmonics from such a generator to such an extent that they may be comparable in intensity to the fundamental. This may be accomplished by providing for the high frequency oscillations of the generator, a path, the impedance of which increases with increase of frequency. The drop of potential across this impedance may then be impressed upon suitably tuned circuits, so that the various harmonics and the fundamental may be separated from each other.

By the two arrangements described above, vacuum tubes of approximately similar characteristics may be employed in connection with a given tuned circuit to generate oscillations which will be constant in intensity and frequency for all the tubes. Such a constancy is of especially great importance when the generator is associated with a system containing tuned circuits, for, on substituting one tube for another, no change need be made in the tuning of the circuits, since the frequency will remain the same.

For the better understanding of this invention, reference is made to the accompanying drawings, in which Fig. 1 represents an embodiment of this invention from which a constant output may be derived: and Fig. 2 represents an embodiment which may be employed as a harmonic generator. Each evacuated vessel in the drawings has

a reference character beside it to indicate its function. Thus, "A" indicates that the vacuum tube is an amplifier; and "G" indicates that the tube is an oscillation genera-
5 tor.

In Fig. 1 the electric discharge device 4, taken in connection with the induction coils 5 and 6 and capacity 7, constitutes an oscillator which generates oscillations of a 10 frequency determined largely by the tuning of the closed circuit including inductance 6 and the capacity 7. 10 is a source of voltage for said generator, its negative pole being connected to the filament 11 and its 15 positive pole being connected through the high resistance 13 to the anode 14. This resistance 13 is of such a high value that the direct current flowing therethrough is practically constant and less dependent on the 20 frequency of oscillation or on slight changes in the impedance between the output electrodes, or other elements of the vacuum tube circuit. A path of low impedance for the 25 oscillating currents between the anode 14 and the filament 11 is provided by means of the condenser 18 and the resistance 19. The condenser 18 has preferably a large 30 capacity, and has consequently small impedance, so that most of the impedance of this path is due to the small resistance 19. The impedance of this resistance is independent of the frequency of the oscillations generated, and therefore, since the space current remains constant, the amplitude of the 35 alternating voltage across the terminals of this resistance is constant; and this voltage drop may be employed, as shown, to impress the generated oscillations upon the input circuit 22 of an amplifier 23. The amplified 40 oscillations in the output circuit 24 may by transformer 25 be impressed upon any suitable receiving or transmitting terminals. The amount of voltage impressed on the amplifier may be regulated by means of the ad- 45 justable contact 26. This amplifier 23 has the peculiar characteristic that it will allow current to flow through it in one direction only. Consequently, although it functions to amplify the oscillations from the genera- 50 tor 4 and to impress them upon the outgoing circuit 27, it will not allow current to flow in the opposite direction, that is, from the outgoing circuit back to the oscillator. The outgoing circuit, therefore, cannot react 55 upon the oscillator to produce distortions in the wave form of the oscillations generated due to fluctuations or changes of the load in said circuit.

Condenser 18 is inserted to prevent the di- 60 rect current from passing through the side circuit containing the small resistance 19. The source of voltage 10 may be also used as the output battery for the amplifier 23. A choke coil 28 is preferably inserted to 65 prevent the oscillation currents from pass-

ing through the battery circuit. Similarly, a condenser 29 prevents the direct current from flowing through the primary winding of the transformer 25.

In Fig. 2, similar to Fig. 1, there is an 70 oscillation generator comprising the evacuated vessel 4, the feed-back connection between the coils 6 and 5, and the capacity 7; and across the output terminals of the vessel is connected the high resistance 13 and 75 the source of voltage 10. A path for the high frequency oscillations is provided by the shunt comprising the inductance 32 and capacity 33 connected across said resistance and source of voltage. The drop of potential across the terminals of inductance 32 is impressed on the input circuit 35 of the unilateral device 36 which is inserted to prevent any reaction of the outgoing circuit upon the oscillation generator. The amplified 80 oscillations in the output circuit 38 are impressed, by transformer 39, upon a system of tuned circuits. Since the impedance of the inductance 32 increases with increase 85 in frequency, it follows that the harmonics 90 generated by the oscillating tube 4 are emphasized considerably more than the fundamental, so that the secondary coil 41 of the transformer 39 contains the fundamental oscillation and its harmonics in approxi- 95 mately the same order of intensity. If now the capacity 42 and inductance 43 are of such values that only oscillations of the fundamental frequency f may pass there- 100 through, then the circuit 45 tuned to the frequency f will receive oscillations of only this frequency by the transformer 46. If the capacity 48 and inductance 49 are tuned to the first harmonic $2f$, then the tuned circuit 50 will receive oscillations of only the 105 frequency $2f$. Similarly the tuned circuit 52 may be made to receive oscillations of only the frequency $3f$, and so on for other circuits tuned to the higher harmonics. The device, therefore, serves as a harmonic generator, and the harmonics derived therefrom 110 may be employed for any purpose desired, such as serving as carrier wave oscillations for low frequency signals in a system for 115 communication.

Condenser 33 prevents the direct current from the source of voltage 10 from passing through the inductance 32, and the choke coil 54 prevents the generated oscillations from passing through the path containing the source of voltage 10 and resistance 13. Condenser 37 is added to prevent the source of voltage 10 from being short-circuited through the primary winding of the trans- 120 former 39.

It is evident that the circuit arrangement disclosed in the drawings may be set up for any type of a vacuum tube oscillator desired and then in accordance with this invention tubes of similar structure may be sub- 125 130

stituted for the original tube without disturbing the remaining element of the associated circuits.

What is claimed is:

5. 1. Means for producing oscillations comprising an electric discharge device, a source of space current for said device, an output circuit connected to said device for supplying the oscillations produced thereby, said 10 output circuit having low impedance for the generated high frequency oscillations and having high resistance for the direct current from the space current source compared with the internal space current resistance of said device, whereby any tendency of 15 the space current to vary is partially compensated by the variation in direct current voltage across the output circuit and the oscillations produced are maintained substantially constant in amplitude irrespective of 20 such tendency.

2. Means for producing oscillations comprising an electric discharge device, a source of space current for said device, an output circuit connected to said device including a path of high resistance for space current compared with the internal output circuit resistance of the device whereby any tendency for variation of the amplitude of the 30 space current in said path is opposed by the change of voltage across said path to maintain substantially constant the amplitude of the oscillations produced, a path of low impedance for the oscillations produced by 35 said means and means for preventing the passage of direct current through said low impedance path.

3. An oscillation generator comprising an evacuated vessel, a source of voltage for said 40 generator, a path of high resistance for the direct current from said source, said resistance having such magnitude that variations occurring in the voltage of said source are not attended with appreciable change in the 45 amplitude of the direct current, a path of low impedance for the generated high frequency oscillations, an outgoing circuit, means for impressing the potential difference set up across said low impedance path upon said outgoing circuit, said means comprising means whereby said outgoing circuit is prevented from reacting upon said generator.

4. An oscillation generator comprising an 55 evacuated vessel, a source of voltage for said generator, a path of high resistance for the direct current from said source, said resistance having such magnitude that variations occurring in the voltage of said source are 60 not attended with considerable change in the amplitude of the direct current, a path of low impedance for the generated oscillations, an outgoing circuit, a unilateral device associated with said outgoing circuit and means for impressing upon said unilateral

device the potential difference set up across said low impedance path.

5. Means for producing oscillations comprising an electric discharge device and a tuned circuit associated therewith, a direct 70 current path connected to the discharge electrodes of said device and including a high resistance of magnitude high with respect to that of the internal resistance of said discharge device between said discharge electrodes and a source of space current in series, said resistance having such large amplitude as to tend materially to compensate for variations in the normal impedance of the electric discharge device associated therewith 80 so as to maintain the direct current substantially at a definite value, and a low impedance path shunted around said direct current path to serve as an output circuit for the oscillations produced. 85

6. Means for producing oscillations of a fundamental frequency and of frequencies harmonic thereto comprising an electron relay and two parallel paths connected in the output circuit of said relay, one of said 90 paths including a source of space current for said relay in series with a resistance of magnitude large with respect to that of the internal space current resistance of said relay and an inductance, and the other of said paths having less inductance whereby the path including the source of space current diverts from the other path a smaller part of the energy of any harmonic frequency oscillations which may be 100 produced by said oscillation-producing means than of the fundamental frequency oscillations produced thereby, and means associated with said other path for selecting therefrom fundamental frequency and harmonic frequency oscillations. 105

7. Means for producing oscillations comprising an electric discharge device, a source of space current connected to said device, a high resistance in series with said source 110 whereby the direct current from said source is made practically independent of slight variations of the voltage of the source, an alternating current path of low impedance in shunt to the path including said source, 115 said low impedance path containing an inductive reactance, said space current path including a larger inductive reactance whereby the relative amplitudes of the harmonic frequency components to the base frequency components of the oscillations diverted by said alternating current path are higher than in the total oscillations of the two paths.

8. Means for producing oscillations comprising an electric discharge device, a source of space current for said device, a resistance in series with said source of magnitude high with respect to that of the internal space current resistance of said device so as to keep 125 130

substantially constant the current from said source, and an impedance path offering higher impedance to high frequency current than to low frequency current in parallel 5 with the path including said high resistance.

9. In combination, an electric discharge device having an input circuit and an output circuit, means for impressing an alternating electromotive force upon said input circuit, 10 said output circuit comprising two parallel branches, one of said branches including a space current source for said device and a resistance in series therewith, said resistance having a magnitude high with respect 15 to the internal resistance of said device so as to maintain the direct current therethrough at substantially the same value irrespective of slight variations of the ratio of the applied space current electromotive force 20 to the impedance of the device whereby the oscillations produced are maintained substantially constant, and means coupled to the other of said branches for selecting therefrom current of a frequency harmonic to 25 that of the electromotive force impressed upon said input circuit.

10. Means for producing oscillations comprising an electric discharge device having coupled input and output circuits, a source 30 of space current for said device, a resistance in series with said source of a magnitude high with respect to the space current resistance of said discharge device so as to render the direct current therethrough of 35 substantially the same magnitude for different electric discharge devices of the same general character and impedance connected in the circuit so that the amplitude of the oscillations generated will not be dependent 40 upon the particular discharge device used, an alternating current path of low impedance also connected to said device, and means for preventing the flow of direct current through said path.

45 11. Means for producing oscillations comprising an electric discharge device having a cathode, an anode and an impedance controlling element, a source of space current and a resistance connected in series between 50 said anode and cathode of magnitude high with respect to that of the internal resistance of said device between said anode and cathode whereby the direct current is kept substantially constant to hold constant the 55 amplitude of the oscillations produced, and a path of low impedance connected to said high resistance and affording an alternating current by-pass therearound for diverting therefrom the harmonic oscillations produced.

60 12. Means for producing oscillations comprising an electric discharge device, a source of space current therefor, a direct current path including a resistance in series with 65 said source of magnitude high with respect

to the internal space current resistance of said device so that the direct current from said source is made substantially independent of slight fluctuations in the characteristics of any of the circuit elements, a path of 70 low impedance in shunt to said direct current path, said two paths having such relative impedances for alternating currents that the low impedance path diverts from the direct current path a larger proportion 75 of the harmonic frequency oscillations than of the fundamental frequency oscillations and selective circuits associated with said low impedance path for separating the fundamental and harmonic oscillations produced.

13. Means for producing oscillations comprising an electric discharge device having output and input circuits connected in feedback relation to produce sustained oscillations, a source of space current for said device having a resistance in series therewith of magnitude high with respect to the internal space current resistance of said device 85 so as to keep substantially constant the current from said source, an alternating current path shunted around the path including said source and resistance, said alternating current path having an impedance which relatively 90 to the impedance of said shunted path is 95 lower for harmonic frequency currents than for the fundamental frequency oscillations produced, and means connected to said alternating current path for selecting currents of the fundamental and of the harmonic frequencies therefrom.

14. Means for producing oscillations comprising an electric discharge device having a space current path including a high resistance element and an alternating current 105 path in parallel, said resistance having such magnitude as to render the direct current therethrough of substantially the same magnitude for small variations in the electromotive force of the space current source in 110 said space current path, and means to select currents of different frequencies from said alternating current path.

15. Means for producing oscillations comprising an electric discharge device and circuits therefor including a space current path having a high resistance element and an alternating current path, said resistance having such magnitude as to render the direct current therethrough of substantially the same magnitude for small variations in the electromotive force of the space current source in 115 said space current path, and means for selecting a plurality of currents of different frequencies from said alternating current path.

16. A thermionic repeater having a cathode, an anode and an impedance control element, a space current circuit connecting said cathode and said anode and including in 120

- series relationship a space current source and a high resistance, an alternating current path in parallel with said space current path, and means for utilizing the potential 5 set up across a portion of said alternating current path, the resistance of said space current path being high with respect to the internal space current resistance between said cathode and anode so as to swamp the 10 effect upon the value of the unidirectional space current caused by the impedance control element.
17. In combination, two thermionic repeaters each having a cathode, an anode and 15 an impedance control element, one of said repeaters having an output circuit comprising a high resistance space current path and an alternating current path connected in parallel therewith, the resistance of said 20 space current path being high with respect to the internal resistance of said repeater for space current so as to swamp the effect which the impedance control element produces in the value of the unidirectional space 25 current, and means connecting the cathode and impedance control element of the other repeater to points in said alternating current path.
18. An oscillator comprising an electric 30 discharge device having coupled output and input circuits, a source of space current for said device, and a resistance in series with said source, said resistance being of such magnitude that the tendency of variations in 35 the impedance of the device to cause variations in the unidirectional space current is submerged by the effect of the resistance.
19. An oscillator comprising a thermionic 40 discharge device having coupled output and input circuits, a space current path for said device including a source of space current and a resistance in series therewith of such magnitude that the tendency of variations in the impedance of the device to cause 45 variations in the unidirectional space current is submerged by the effect of the resistance, and a low impedance path in parallel to said space current path for transferring alternating current energy to a work 50 circuit.
20. In combination, a thermionic repeater having a cathode, an anode and an impedance control element, an inductance connecting said cathode and said impedance control 55 element, means for impressing across the terminals of said inductance an alternating electromotive force of a fundamental frequency together with its harmonic frequencies, an output circuit connecting said 60 cathode and anode, said output circuit in- cluding a space current path having a resistance of magnitude high with respect to the internal resistance between said cathode and anode, and means associated with said output circuit for selecting therefrom currents of said harmonic frequencies. 65
21. In combination, a thermionic repeater having a cathode, an anode and an impedance control element, an impedance element, the impedance of which increases with frequency connecting said cathode and said impedance control element, means for impressing across the terminals of said impedance element an alternating electromotive force of a fundamental frequency together with its harmonic frequencies, an output circuit connecting said cathode and anode, said output circuit including a space current path having a resistance of magnitude high with respect to the internal resistance between said cathode and anode, and means associated with said output circuit for selecting therefrom currents of said harmonic frequencies. 70
22. A thermionic device having an output circuit comprising a space current path and an alternating current path in parallel, said space current path including a space current source and a high resistance in series therewith, said alternating current path including a capacity element and an inductance element in series, and a thermionic repeater having input terminals directly connected to the terminals of said inductance element. 75
23. A thermionic device having an output circuit comprising a space current path and an alternating current path in parallel, said space current path including a space current source, a high resistance, and a large inductance all in series, said alternating current path including a capacity element and a small inductance in series, and a thermionic repeater having input terminals directly connected to the terminals of said small inductance element. 80
24. A harmonic generator circuit comprising an electron discharge device having an input circuit and an output circuit with two parallel branches, one of which branches includes a source of discharge current and a high resistance and the other of which is coupled to a work circuit, said resistance having such a magnitude as to maintain the direct current therethrough substantially constant irrespective of changes in the impedance of said device. 85
- In witness whereof, I hereunto subscribe my name this 1st day of June, A. D. 1917.
- EDWARD O. SCRIVEN.
